DESIGN FOR A LAMP

Edward C. Godfrey, Detroit, Mich.

Application March 26, 1934, Serial No. 51,180

Term of patent 14 years

To all whom it may concern:

Be it known that I, EDWARD C. GODFREY, a citizen of the United States, residing at Detroit, county of Wayne, State of Michigan, have invented a new, original, and ornamental Design for a Lamp, of which the following is a specification, reference being had to the accompanying drawing forming part thereof.

Figure 1 of the drawing illustrates a side elevation of my new design for a lamp in position for

use as a table lamp, the shade being shown in dotted outline, and

Figure 2 of the drawing illustrates a plan looking downwardly on the base taken on line 2—2 of Fig. 1, the shade being omitted.

I claim:

The ornamental design for a lamp as shown and described.

EDWARD C. GODFREY.
